WINDOW SASH CONSTRUCTION

Antonino Cacciola, Brooklyn, N. Y.

Application October 8, 1932, Serial No. 636,913

5 Claims. (Cl. 20—12)

This invention relates to improvements in removable window sash construction and the primary purpose of this invention is to provide a removable sash construction for windows whereby the window sash may be removed from the frame for the purpose of cleaning or washing.

A further object of this invention is to provide a removable window sash of the above mentioned character to be released from the window frame by means of a movable vertical guide rail having edges and ends so constructed as to move the guide rail vertically as well as horizontally so that the guiding face will be moved out of engagement with the vertical contacting face 15 of the window sash.

A still further object of this invention is to provide a movable guide rail adapted to be moved into and out of engagement with the window sash by means of a lever pivotally carried by the vertical window frame and having a lost motion connection with the guide rail.

A still further object of this invention is to provide locking means for the movable guide rail whereby the same may be held in its operative position so that the guiding face will engage the vertical contacting face of the window sash.

Other objects and advantages of the invention will become apparent during the course of the 30 following description forming a part of this specification and in which,

Figure 1 is a top plan view of a window sash construction embodying this invention, and illustrating the vertical guide rail in its operative position;

Figure 2 is a top plan view of a window sash construction showing one of the vertical frame members in cross-section to illustrate the movable guide rail in its released position whereby the window sash may be readily removed from the window frame;

Figure 3 is a transverse cross-sectional view taken on line 3—3 of Figure 2, looking in the direction of the arrows, illustrating one of the window sashes partially removed and further illustrating the guide rail out of engagement with the vertical edges of the window sash;

Figure 4 is an enlarged detail view taken on line 4—4 of Figure 1, looking in the direction of the arrows illustrating the operating lever and combined latch for simultaneously unlocking and raising the movable guide rail when it is desired to remove the window sashes from the frame;

Figure 5 is a perspective view of the wrench

employed for operating the pivoted lever and combined latch to displace the guide rail from its window engaging position to the position shown in Figure 2 whereby the sash may be readily removed;

Figure 6 is a view similar to Figure 4 with the lever in shifted position;

Figure 7 is a detail sectional view showing the wrench socket in the window stile; and

Figure 8 is a detail sectional view taken on line 8—8 of Figure 7.

In the drawings wherein for the purpose of illustrating the invention and wherein like reference characters will be employed to designate like parts throughout the same, the reference character 6 will generally be employed to designate a window frame having vertical side rails 7, top and bottom rails 8 and 9 suitably grooved for connection to the vertical side rails 7. The sill rail 10 depends from the lower rail 9 in the usual manner.

Extending between the top and bottom rails 8 and 9 are guide rails 11 and 12 held in place by having the ends thereof received in grooves 13 extending transversely through the top and bottom rails 8 and 9. Guide rail 12 is provided with a rib 14 which extends the entire length thereof while the guide rail 11 is provided with a similar rib 15, said guide rail and rib only extend downwardly from the top rail 8 to a position half the height of the window frame.

The guide rails 11 and 12 are held in the vertical side rail 7 by means of front and back strips 16 and 17 secured to the vertical side rails 7 by nails or screws. The inner edges of the front and back strips 16 and 17 are closed by the guide rails 11 and 12 and vertical strips 18 are interposed between the guide rails 11 and 12 and to the rear strip 17 for the purpose of guiding the window in the frame.

Slidably guided by the guide rails 11 and 12 are upper and lower window sashes 19 and 20 and window sashes 19 and 20 are counter-balanced by sash weights 21 and 22 respectively connected to the sash chains 23 and 24 passing over a sash pulley 25. The sash weights 21 and 22 operate in the spaces formed by the vertical side rails 7, front and rear strips 16 and 17 and guide strips 11 and 12.

The lower portion of one of the vertical side frame members 7 may be provided with a movable guide rail 26 having a guide rib 27 similar to the guide ribs 14 and 15. Said guide rail 26 is slidably mounted between the front and rear strips 16 and 17 as clearly shown in Figure 3.

and is provided at its ends with bevelled portions 28. The lower end 27 is adapted to be engaged in a bevelled groove 29 while the upper edge 28 is adapted to engage a bevelled end 30 of the upper guide rail 11 whereby vertical movement of the guide rail 26 will cause the same to move outwardly and away from the window sash frames 19 and 20.

Means is provided for moving the guide rail 26 and said means comprises a plate 31 secured to the inner side of the upper guide rail 11 by means of screws 32. The metal plate 31 is provided with a central opening in which is journaled a shaft 33 having mounted on the inner end thereof a lever 34 by means of a block 34a. The free end of the lever 34 is rounded or bevelled as at 35 so that the same will engage the upper edge of the guide rail 26 and force the same home after it has been released. Connected to the free end of the lever 34 is a pin 36 to which is connected one end of a rod 37 while the opposite end of the rod is provided with a spherical member 38 for limiting the movement of the rod 37 through an eyelet 39 carried by the inner wall of the guide rail 26. It will be noted that as the shaft 33 is rotated from the position shown in Figures 1 and 4, the rod 37 will be raised as shown in Figure 6 until the spherical end 38 engages the eye 39 whereby the guide rail 26 will be raised vertically and said vertical movement will cause the edge 38 on the upper end thereof to engage the lower edge 30 of the guide rail 11 to move the guide rail 26 laterally away from the window sash frames 19 and 20 as is illustrated in Figures 2 and 6. When the pivoted lever 34 is in the position shown in Figures 1 and 4, it engages a plate 40 secured to the upper end of the guide rail 26 by means of screws 41 in order to drive the guide rail 26 home to its seated position as shown in Figure 1.

The shaft 33 is provided with a key extension 42 as shown in Figure 8 so that the socketed end 43 of a wrench 44 may engage the socket 42 for the purpose of rotating the lever 34. The key extends into an opening 42a in the rail 11.

Before the lower guide rail 26 has been moved to its releasing position as shown in Figure 3, the upper window sash 19 should be moved downwardly to its limit as shown in Figure 2, both sash chains 23 and 24 being disconnected from the sashes and while the sash weights are raised, the sash chains are attached to the hooks 23a shown in Figures 2 and 3 to hold the weights in position until the sashes are returned to the window frame.

It is to be understood that the lower portions of each of the vertical guide rails 11 and 12 may be provided with movable guide portions and that other changes in the shape, size and arrangement of parts may be resorted to without departing from the spirit of the invention or the scope of the subjoined claims.

I claim:—

1. A window construction of the character described, comprising a window frame having side, top and bottom rails, window sashes slidably mounted in the window frame, a pair of guide rails carried by the side rails, one of said guide rails being provided with a stationary upper portion and a movable lower portion, a shaft journaled in the upper stationary portion of the guide rail in close relation to the upper portion of the lower movable guide rail, a pivoted lever secured to said rotary shaft, a link connecting the movable guide section to the pivoted lever,

and means formed on the ends of the movable guide sections and the lower end of the stationary guide rail for guiding the movable guide member into and out of engagement with the window sashes.

2. A window construction of the character described, comprising a window frame, window sashes slidably mounted in the window frame, a pair of guide rails carried by the window frame, one of said guide rails having an upper stationary portion and a lower movable section, said stationary portion having its lower end bevelled to coincide with a bevelled portion of the upper end of the lower guide rail, a bevelled slot formed in the lower rail of the window frame adapted to cooperate with the bevelled lower end of the lower guide rail, a rotary shaft carried by the lower end of the upper stationary guide member, a lever secured to the rotary shaft, a link connecting the free end of the rotary lever to the movable guide section and means for rotating the rotary shaft to cause the lower movable section of the guide rail to move toward and away from the window sashes and simultaneously lock the movable section in its operative position.

3. A window construction of the character described, comprising a window frame having side, top and bottom rails, window sashes slidably mounted in the window frame, a pair of guide rails carried by the side rails, one of said guide rails being provided with a stationary upper portion and a movable lower portion, said movable lower portion being provided with bevelled edges in reverse order to cause the lower portion to be moved laterally when drawn upwardly, a shaft having a squared end exposed to the exterior of the window opening journaled in the upper stationary portion of the guide rail in close relation to the upper portion of the lower movable guide rail, a pivoted lever secured to said rotary shaft, a link having one of its ends connected to the pivoted lever, and a sliding connection for the opposite end of the link with the movable guide strip.

4. A window construction of the character described, comprising a window frame having side, top and bottom rails, window sashes slidably mounted in the window frame, a pair of guide rails carried by the side rails, one of said guide rails being provided with a stationary upper portion and a movable lower portion having bevelled ends in reverse order to cause the movable member to be moved laterally away from the window when drawn upwardly, a stub shaft having a squared end journaled in the upper stationary portion of the guide rail in close relation to the upper portion of the lower movable guide rail, said squared portion of the shaft being presented to the interior of the window frame and sliding sashes, a crank arm rigidly secured to the rotary shaft, a link having one of its ends pivotally secured to the free end of the crank, a sliding connection between the movable guide rail and the free end of the link, and means for rotating the stub shaft including a wrench having a socket end adapted to engage the squared end of the rotary shaft.

5. A window construction of the character described, comprising a window frame having side, top and bottom rails, window sashes slidably mounted in the window frame, a pair of guide rails carried by the side rails, one of said guide rails being provided with a stationary upper portion and a movable lower portion, said lower portion being provided with bevelled ends in reverse
